UNITED STATES PATENT OFFICE.

JAMES C. FULTON, OF YONKERS, NEW YORK, ASSIGNOR TO ALEXANDER SMITH & SONS
CARPET COMPANY, OF YONKERS, NEW YORK, A CORPORATION OF NEW YORK.

DESIGN FOR CARPET.

51,261.

Specification for Design. Patented Sept. 11, 1917.

Application filed August 3, 1917. Serial No. 184,334. Term of patent 3½ years.

To all whom it may concern:

Be it known that I, JAMES C. FULTON, a citizen of the United States, residing at Yonkers, in the county of Westchester and State of New York, have invented a new, original, and ornamental Design for Carpet, of which the following is a specification, reference being had to the accompanying drawing, forming a part thereof.

The figure is a face view of a piece of carpet showing the design.

The design is intended to be worked into or upon carpets, rugs or similar fabrics in such colors as may be desired.

I claim:—

The ornamental design for carpet as shown and described.

JAMES C. FULTON.
